UNITED STATES PATENT OFFICE.

EDWIN G. STAUDE, OF MINNEAPOLIS, MINNESOTA, ASSIGNOR, BY MESNE ASSIGNMENTS, TO UNITED STATES ENVELOPE COMPANY, OF SPRINGFIELD, MASSACHUSETTS, A CORPORATION.

ENVELOP-MACHINE.

1,193,627.

Specification of Letters Patent. Patented Aug. 8, 1916.

Application filed November 30, 1912. Serial No. 734,377.

To all whom it may concern:

Be it known that I, EDWIN G. STAUDE, a citizen of the United States, resident of Minneapolis, in the county of Hennepin, 5 State of Minnesota, have invented certain new and useful Improvements in Envelop-Machines, of which the following is a specification.

My invention relates to envelop machines 10 of the type wherein the blanks are initially folded by one mechanism, and then have their direction of movement changed in a secondary or supplemental folding mechanism, and one object of the invention is to 15 provide improved means for holding the blank down on the carrier as it passes from the initial folding mechanism to the secondary or supplemental folding mechanism.

A further object is to provide means 20 which will positively prevent the loose flaps of the blank from sticking or catching to any part of the machine during the passage of the blank from one folding means to another.

25 Other objects of the invention will appear from the following detailed description.

The invention consists generally in various constructions and combinations, all as hereinafter described and particularly pointed 30 out in the claims.

In the accompanying drawings forming part of this specification, Figure 1 is a plan view of a portion of an envelop machine embodying my invention, Fig. 2 is a sectional 35 view on the line $x-x$ of Fig. 3, Fig. 3 is a sectional view on the line $y-y$ of Fig. 2, Fig. 4 is a detail sectional view illustrating the means for holding the blank down upon the carrier, Fig. 5 is a detail sectional view, 40 showing the device for delivering fluid pressure to the surface of the blank, Fig. 6 is a detail view showing the means for feeding the blank into the supplemental creasing and folding mechanism.

45 In the drawing, 2 represents the frame of the machine and 3 and 4 upper and lower feed belts between which the blanks are delivered from the initial folding mechanism (not shown). These belts are driven prefer- 50 ably through a shaft 5 geared to a driving shaft 6. Near the feed belts 3 and 4 I prefer to provide rolls 7 and 8 to receive the blanks and deliver them upon a single roll 9 from

which the blanks pass to a feed plate 10. At the inner edge of the feed plate I pro- 55 vide a way 11 for a feed belt 12 that is pro- vided with hooks 13 adapted to engage the edge of the blank and feed it to the secondary creasing and folding mechanism. A carrier belt 14 passes around rolls 15 and 16, 60 (see Fig. 2) and over rolls 17 and 18 mounted in the brackets 19 and 20, said brackets having hubs 21 in threaded engagement with screw shafts 22 mounted in said frame. The hubs 21 have rods 21' connect- 65 ing them in pairs on opposite shafts and are provided with rolls 23 which operate as guides for the carrier belt, said belt operating, as shown plainly in Fig. 2, in the direction of movement of the feed belts 3 70 and 4.

To direct the blanks to their proper position on the feed belts I prefer to provide a guide 24 that is laterally adjustable by means of slotted bars and bolts, as indicated 75 at 25. This lateral movement of the bar adapts the mechanism for handling blanks of different sizes.

When the blank is delivered from between the rolls 7 and 8 it passes over the roll 9 and 80 the guide plate 24 onto the carrier belt 14 and is fed forward until it is checked by a stop 26 adjustably mounted at 27 on the brackets 19. Near this stop 26 a second way 11 is provided for the second feed belt 85 12. These ways and belts, disposed upon opposite sides of the rolls 17 and 18, as shown in Fig. 4, being substantially the same, I will designate them by the same reference numerals: 90

The blanks falling upon the carrier belt 14 will be moved thereby into contact with the stop 26 for the purpose of centering and alining the blanks with respect to the feed belts 12 preparatory to changing the direc- 95 tion of movement of the blanks toward the secondary creasing and folding mechanism. I have found, however, in delivering the blanks to this carrier belt that considerable difficulty is experienced in holding the light 100 paper blank down on the belt so that the blank will be properly alined and centered before beginning its movement toward the mechanism for performing the final creasing and folding operation. This difficulty in 105 holding the blank in place is due partly to

the movement of the carrier belt itself and principally, perhaps, to the fact that the blanks are not sufficiently heavy to stay down on the carrier belt of their own weight, but are composed of comparatively thin, light material, usually employed in envelop stock, and are therefore jarred or thrown out of place by the moving mechanism. Evidently if the blanks are not properly 10 centered and alined before entering the secondary creasing rolls the final step in the operation will not be properly performed. To hold the blanks down on the carrier belt and insure contact with the stop and the 15 centering and alining of each blank, I provide a mechanism which I will now describe in detail.

29 is a shaft mounted in brackets 30 on the machine frame and provided with a key-way 31.

32 represents hubs slidable on the shaft 29 and having set screws 33 for locking the hubs in the key-way. Pipes 34 and 35 are carried by said hubs and have flexible connections 36 with a compressed air supply pipe 37 provided with a regulating valve 38. By opening or closing this valve the flow of air pressure through the pipes is controlled. The pipes 34 and 35 are each provided in 30 their underside with a longitudinal slit 39 and within each pipe 34 and 35, above the carrier belt, I arrange a tube 40 having a spiral slot 41 therein. Rods 42 are secured to the outer ends of the tubes 40 and close 35 the ends of the tubes against the escape of the air pressure. Brackets 43 are adjustably mounted on a rod 44 that is parallel with the shaft 6 and the outer ends of the rods 42 have bearings in said brackets and are provided with spiral gears 45 meshing with similar gears 46 slidably mounted on the shaft 6. By loosening the set screws 33 and the brackets 43 the rods 42 may be moved back and forth over the carrier belt to adapt them 40 for blanks of different sizes. When air pressure is delivered to the pipes 34 and 35 and flows into the tubes 40, it will be evident that as these tubes revolve through their connection with the rods 42 a stream of air will 45 flow down through the slits 39 when portions of the spiral slots 41 are in register with said slits and the air, contacting with the blank and with the loose flaps, will hold them down to the position indicated in Figs. 4 and 5 and insure the positive feed of the 50 blanks to the stop 26 and also prevent the loose flaps from swinging up and catching on any portion of the machine and interfering with the rapid and accurate feed of the 55 blanks.

In addition to driving the rods 42, the shaft 6 has a driving connection at 47 with the shaft 5 and with the rolls 7, 8 and 9 for operating them continuously. The feed 60 belts 12 have their sprocket wheels mounted

in bearings 48 which are adjustable in slotted bars 49 carried on the brackets 19 and 20. By revolving the screw shafts 22, the feed belts may be moved back and forth across the machine to change their position 70 with respect to the carrier belt and the secondary creasing and folding mechanism. This adjustment of the feed belts and the parts connected therewith adapts the machine for handling blanks of different sizes. 75 This feature I make no claim for in this application, as it forms a portion of the subject matter of my co-pending application Serial No. 571,248, filed July 9, 1910. From the feed belts the blanks pass to creasing 80 rolls 51 and from thence to belts 52 which deliver the blanks to the gluing and folding devices.

To prevent the blanks from passing over the pipes 34 and 35 I prefer to provide a 85 guide 54 mounted on the pipe 35 and upwardly inclined to a point above the roll 9. In case the blank should tilt upwardly in passing over the roll 9 it will contact with the guide 54 and be directed thereby down 90 under the pipes 34 and 35 upon the carrier belt.

In the operation of the machine, the partially folded blanks pass through the rolls 7 and 8 and dropping upon the carrier belt, 95 are fed thereby into contact with the stop 26. At this time the air pressure will be admitted from above in the manner described, and the blank will be held down on the belt and against the stop to insure the centering and alining of the blank and the loose flaps of the blank will also be held down and prevented from interfering in any way with the proper feeding of the blank in a direction at right angles to its previous movement. The rotation of the tubes 40 is timed with the movement of the blanks to supply a stream of air the width of each blank and from the time it contacts with the stop until delivered to the creasing rolls of the secondary folding mechanism. In this way I am 105 able to positively hold the blank on the carrier belt and in contact with the stop and insure proper alining and centering of the blank with respect to the feed belts and the 110 secondary folding mechanism. 115

In various ways the means for delivering the air pressure to the blanks may be modified and still be within the scope of my invention.

120 I claim as my invention:—

1. In an envelop machine, the combination with means for feeding blanks having folded flaps, of means for delivering air under pressure upon said blanks in a blast 125 crossing said folded flaps, whereby the same are maintained in folded position and means for coördinating the operations of said blank feeding means and said air delivering means, whereby the action of said last men- 130

- tioned means is inaugurated simultaneously with the beginning of the movement of the blank.
2. In an envelop machine, the combination with means for successively feeding blanks, of means for delivering air under pressure upon each blank and means for co-ordinating the operations of said feeding means and said air delivering means, whereby by the action of the last mentioned means is inaugurated simultaneously with the beginning of the movement of each blank.
3. In an envelop machine, the combination with a blank feeding means, of means for successively projecting blanks thereon, means for delivering air under pressure upon each blank and means for inaugurating the operation of said air delivering means simultaneously with the beginning of movement of each blank by said feeding means, whereby each blank is maintained in predetermined position during the whole of its movement on said feeding means.
4. The combination, with an initial feeding means, of a secondary feeding means operating at an angle with respect to said initial feeding means and adapted to receive a blank therefrom, means for centering the blank on said secondary feeding means, means for delivering air under pressure upon the blank and means for inaugurating the operation of said air delivering means simultaneously with the arrival of each blank against said centering means, whereby each blank is maintained in the position determined by said centering means during its movement by said secondary feeding means.
5. The combination, in an envelop machine, with an initial blank feeding means, of a secondary feeding means operating at an angle to said initial feeding means, means for centering the blank upon said secondary feeding means, means for delivering air under pressure upon the forward and rear edges of said blank and means for inaugurating the operation of said air delivering means simultaneously with the arrival of each blank against said centering means, whereby each blank is maintained in the position determined by said centering means during its movement by said secondary feeding means.
6. The combination, with an initial blank feeding means, of a secondary feeding means operating at an angle to said initial feeding means, a stop in the path of the blank for centering it upon said secondary feeding means, means for delivering air under pressure upon said blank and means for inaugurating the action of said air delivering means simultaneously with the engagement of the blank with said stop, whereby the blank is maintained in the position determined by said stop during its movement by said secondary feeding means.
7. The combination, with an initial blank feeding means, of a secondary feeding means operating transversely with respect to said initial feeding means, means for centering the blank on said secondary feeding means, means for delivering air under pressure upon the opposite edges of the blank and means for inaugurating the operation of said air delivering means simultaneously with the arrival of each blank against said centering means, whereby the blank is maintained in the position determined by said centering means during its movement by said secondary feeding means.
8. The combination, with an initial blank feeding means, of a secondary feeding means operating transversely with respect to said initial blank feeding means, a stop in the path of the blank, a carrier operating in the direction of movement of said initial feeding means to feed the blank into contact with said stop and center it with respect to said secondary feeding means, a pneumatic device for holding the blank in its centered position upon said carrier and said secondary feeding means and means for inaugurating the action of said pneumatic device simultaneously with the arrival of the blank against said stop, whereby the blank is maintained in the position determined by said stop during its movement by said secondary feeding means.
9. The combination, with an initial blank feeding means, of a secondary feeding means operating transversely with respect to said initial feeding means, a stop in the path of the blank delivered to said secondary feeding means, means for feeding the blank into contact with said stop, means for delivering air under pressure upon the forward and rear portions of the blank and means for inaugurating the action of said air delivering means simultaneously with the engagement of said blank with said stop, whereby the blank is maintained in centered position during its movement by said secondary feeding means.
10. The combination, with an initial blank feeding means, of a secondary feeding means operating transversely with respect to said initial feeding means, means for delivering air under pressure upon the blank on said secondary feeding means and means for co-ordinating the operations of said secondary feeding means and said air delivering means, whereby the action of the last mentioned means is inaugurated simultaneously with the beginning of the movement of the blank on said secondary feeding means.
11. The combination, with a blank feeding means, of means for delivering air under pressure upon a blank carried by said feeding means, said air delivering means being adjustable to adapt it for blanks of different sizes and means for co-ordinating the op-

erations of said feeding means and said air delivering means, whereby the action of the last mentioned means is inaugurated at the beginning of the movement of the blank on 5 said feeding means.

12. The combination, with a blank feeding means, of means for delivering air under pressure upon the blank carried by said feeding means, said air delivering means including a pipe having a discharge opening therein and a rotating tube within said pipe and provided with a spiral opening adapted to register by degrees with the opening in said pipe as said tube revolves, and connected with a source of air under pressure. 10

13. The combination, with a blank feeding means, of means for delivering air under pressure upon the blank carried by said feeding means, said air delivering means including inner and outer tubes having a relative revolving movement and openings through which currents of air are discharged upon the blank, means for supplying air under pressure to the inner tube. 20

14. The combination, with a blank feeding means, of means for delivering air under pressure upon the blank carried by said feeding means, said air delivering means including a pipe having a longitudinal slot therein and a rotating tube having a spiral slot therein arranged within said pipe and connected with a source of air under pressure. 30

15. The combination, with a blank feeding means, of a rod mounted above the same transversely thereof, pipes slidable on said rod and having longitudinal slits therein, tubes fitting within said pipes and having 35

spiral slots formed therein, said tubes and pipes overhanging the blank upon said feeding means, means for delivering air under pressure to said tubes, and means for revolving said tubes. 40

16. The combination, with an initial blank feeding means, of a secondary feeding means operating transversely with respect to said initial feeding means, a stop in the path of the blank delivered to said secondary feeding means, a guide over which the blank passes to said secondary feeding means, said stop and guide engaging the forward and rear portions respectively of the blank and centering the same on said feeding means, and forming a guide for the blank on said feeding means, and means for holding the blank in its centered position. 45 50 55

17. The combination, with an initial blank feeding means, of a secondary blank feeding means operating at an angle thereto, a stop in the path of the blank as it is fed to said secondary feeding means, a pipe arranged above said secondary feeding means and having means for delivering air under pressure upon the blank thereon, a guide arranged to direct the blank from said initial feeding means beneath said pipe upon said secondary feeding means and means for inaugurating the delivery of air from said pipe simultaneously with the engagement of the blank with said stop. 60 65 70

In witness whereof, I have hereunto set my hand this 21st day of November, 1912.

EDWIN G. STAUDE.
